(57) CLAIM

The ornamental design of a nasal support device, substantially shown and described.

DESCRIPTION

FIG. 1 is a top perspective view of an embodiment of a nasal support device;

FIG. 2 is a bottom perspective view thereof;

FIG. 3 is a first side view thereof;

FIG. 4 is a second side view thereof, wherein the second side view is opposed to the first side view;

FIG. 5 is a third side view thereof;

FIG. 6 is a fourth side view thereof, wherein the fourth side view is opposed to the third side view;

FIG. 7 is a top view thereof; and,

FIG. 8 is a bottom view thereof. The broken lines within the claimed design are for illustrative purposes only. The broken lines within the claimed design indicate unclaimed subject matter forming no part of the claimed design.
